SURFACE DECORATING MACHINE

Robert H. McBean, Fairview Village, Ohio, assignor to Oxford Varnish Corporation, Detroit, Mich., a corporation of Michigan

Application February 9, 1934, Serial No. 710,508

10 Claims. (Cl. 101—154)

This invention relates to a surface decorating machine, such as a graining machine, and is especially concerned with the provision of a mechanism for transferring a design from a pattern roll to a transfer or offset roll, which roll is thereafter brought into rolling contact with the material to be decorated, thereby transferring the design to such material. This, therefore, is the general object of the present invention.

Another object of the invention is to provide a mechanism which will readily and quickly transfer pigment from a predetermined circumferential portion of a power-driven pattern roll to an offset printing roll.

A further object of the invention is to provide an apparatus which will enable the transfer of pigment from a pattern roll, so as to completely cover a transfer roll in a circumferential direction without danger of overlapping of the pattern on the transfer roll, and regardless of the relative sizes of the two rolls.

Another object is to provide a mechanism whereby an offset roll may be manually moved toward the pattern roll and will be prevented from engagement therewith until a predetermined point on the pattern roll is reached, and will then be locked in engagement with the pattern roll until a second predetermined point in the revolution of the pattern roll is reached, at which time the rolls will automatically separate.

Other objects of this invention will become more apparent from the following description, reference being had to the accompanying drawings, which illustrate a preferred form of the invention. The essential characteristics of the invention will be summarized in the claims.

In the drawings, Fig. 1 is a side elevation of the machine embodying my invention; Fig. 2 is a fragmentary view, similar to Fig. 1, but illustrating certain of the parts in different positions; Fig. 3 is an enlarged fragmentary elevation, similar to Figs. 1 and 2; Figs. 4 and 5 are fragmentary vertical sections, as indicated by the lines 4—4 and 5—5, respectively, on Fig. 3; Fig. 6 is a fragmentary horizontal section as indicated by the line 6—6 on Fig. 3; Fig. 7 is a section similar to Fig. 6, but illustrating certain of the parts in the position shown in Fig. 1; Fig. 8 is a sectional detail of a modified form of control mechanism; Fig. 9 is a vertical section as indicated by the line 9—9 on Fig. 8.

When decorating materials with a design such as an imitation wood grain, it is often desirable to manually roll an offset roller, to which the

design in pigment has previously been transferred from the pattern roll, across the object to be decorated. In the past it has been found difficult to transfer the pattern to such offset roll, as the pressure between the offset roll and the pattern roll, during the transfer of the pigment therebetween is critical. Likewise, it has been difficult to make use of a power-driven pattern roll, because of the frequent overlapping of the pattern on the offset roll and consequent blurring of the design on the material to be decorated.

The mechanism of the present invention overcomes such difficulties by providing a support for the offset roll, which, together with the offset roll, is manually moved toward the pattern roll, and by incorporating a mechanism to prevent contact between the offset and pattern rollers until a predetermined point of revolution of the pattern rolls has been reached, and automatically causing the two rolls to separate after a predetermined portion of a revolution has been effected. The mechanism also is arranged so that the period of contact may be regulated, that is, lengthened or decreased as desired, or the period may be adjusted to start at various points on the pattern roll, as desired. Likewise, provision has been made to regulate the pressure between the offset rolls and the pattern rolls during their actual contact.

Referring again to the drawings, my improved graining mechanism comprises, in general, a frame 10 in which is rotatably mounted a pattern roll 20 driven by any suitable source of power, such as by an electric motor 15 through driving belt 16 and suitable pulleys 17 and 18 secured to the motor shaft and pattern roll respectively. The frame also supports a pigment applicator 50 which applies colors or pigment to the pattern roll. The offset roll is shown at 30, and is removably supported on a frame member 40, which is pivotally connected to the main frame, as at 41.

The pattern roll is supported by a shaft 21, which is rotatably journalled as in bearings 22, secured to the main frame 10. The pattern roll 20 comprises a cylindrical form, carrying on its periphery a suitable offset printing member, such as a printing plate 19 having a design thereon, for instance a simulation of a natural wood or other object impressed thereon.

The design may be produced by any of the well-known processes frequently used for such purposes. Suffice it to say that the design may be in relief on the plate or it may be depressed therein, as desired. The mechanism shown in

the drawings is especially well adapted for the latter type of printing plate.

The inking mechanism or pigment applicator comprises, as shown, a suitable roller 50, mounted

5 in a bracket member 51 and contacting with the periphery of the plate roll 20. As shown, the inking roll 50 rotates with its lower area submerged in ink or pigment carried in a trough or pan 52, supported in any well-known manner by the main frame member 10. A doctor blade, such as is indicated at 53, acts to scrape the excess ink or pigment from the plate before it comes in contact with the offset roll 30.

When it is desired to transfer a pattern to an 15 offset roll 30, the operator grasps the roll by its handles or spindles 31 and places it in a bracket 32, which is slidably mounted in ways 33 on the upper end of the pivoted frame member 40, heretofore mentioned. The entire frame member is 20 then manually rocked about its pivot 41 toward the pattern roll 20.

The pattern roll and offset rolls are prevented from contacting with each other except at a predetermined time. As shown in Figs. 1, 2, and 3 a 25 member or pawl 60 carried by a lever 61, which is pivotally connected to the rocking frame member 40, as at 62, projects toward and engages the periphery 63 of an annular cam member 64, adjustably carried by the pattern roll 20, as will 30 hereinafter be more fully described. The rim 64 is provided with a notch 65, Figs. 3, 4, and 5, which, during the course of rotation of the pattern roll 20, comes into alignment with the member 60, permitting the two rolls to contact 35 with each other, at which time a lower hook-like end or latch portion 66 of the lever 61 drops behind an abutment 67 carried by the frame member 10, positively locking the two members together.

40 Suitable adjustable studs 66a (Fig. 2) one of which is carried by the rocking frame member 40 and the other by the main frame 10, serve to limit the pressure between the two rolls.

After the pattern roll has made a predetermined portion of a revolution, a pin 70, adjustably secured to the periphery of the roll, coacts with the pawl 60 and rocks the lever 61 upwardly against the action of a spring 68, withdrawing the latch portion 66 thereof from engagement 45 with the abutment 67, thereby permitting the offset roll carrier to swing about its pivot 41, separating the two rolls.

As shown in Figs. 6 and 7, the member 60 is 50 preferably pivotally connected by means of a suitable stud 62a to the outer end of the lever 61. The outermost end 67a of the member 60 projects beyond the end of the lever 61 and enters the slot 65 in the cam 64 on the pattern roll, as shown in Figs. 3 and 6. Immediately after such 55 entrance, the spring 68 draws the latch 61 into engagement with the abutment 67, locking the two rolls together.

The continued rotary movement of the pattern roll 20 causes a cam portion 69 of the cam 64 to 60 engage the edge 71 of the member 60, rocking it about its pivot 62 and causing a projection or lug 72 to be swung into the path of the pin 70, heretofore mentioned. Hence, when the pin 70, consequent upon the revolution of the pattern 65 roll, engages the lug 72 as indicated in Fig. 7, it will rock the member 60 together with the lever 61, about the pivot 62, thereby moving the latch portion 66 of the lever out of engagement with the abutment 67, whereupon the frame member 70 75 40, together with the offset roll, will swing, under

the influence of gravity, in a counter-clockwise direction about the pivot 41. A suitable spring-pressed plunger 55, Fig. 4, serves to normally maintain the member 60 in position.

As the rolls separate, the member 60 is automatically reset, that is, moved from the position shown in Fig. 7 to the position shown in Fig. 6. For this purpose a suitable post or cam 75 is secured to the frame member 10 and acts consequent upon the separating movement of the 10 two rolls, (during which movement the member 61 moves to the left in Figs. 6 and 7), to engage the surface 76 of the member 60, thereby rocking it about its pivot and returning it to the same position relative to the lever 61, as is shown in 15 Fig. 6.

To adjust the period of contact,—that is, to lengthen or decrease the periphery of the pattern roll which contacts with the offset roll, it is desirable to move either the pin 70 or the cam 20 ring 64 relative to each other. As shown in the drawings, both the cam ring and the pin are adjustable relative to each other and to the pattern roll 20. The pin 70 is shown as carried by an annular ring member 71, which is provided 25 with suitable arcuate slots 78, through which bolts 79 pass, securing the ring in an adjusted position to the roll 20. Hence, when it is desired to adjust the position of the pin 70, to change the point at which the two rolls separate, the 30 operator merely loosens the bolt 79 and moves the ring relative to the pattern roll.

The cam member 63, which regulates the point at original contact between the two rolls, is likewise adjustable. As shown, the cam 64 is provided 35 with an annular portion 80, which has slots 81, through which suitable bolts 82 pass. In this way, both the point of contact and the point of release between the two rolls may be readily regulated relative to each other or both may be moved 40 the same distance to change the length or location of the area of the pattern roll which is to be transferred to the offset roll.

It will be noted that I have so arranged my mechanism that it is well adapted to cover the 44 complete periphery of the offset roll, without overlapping. However, by reason of the sliding connection between the frame member 40 and the offset roll 30, the mechanism is readily adjustable 48 for various diameters of offset rolls. A suitable 54 adjusting by merely moving the screw 34 is provided to lock the bearing member 32 in an adjusted position.

Figs. 8 and 9 illustrate a modified form of control mechanism. As shown, there is provided a 58 latch member 60a, pivoted as at 62a, to the arm 61, and normally retained in a fixed position by a pawl 90 carried by the latch member 60a and entering a recess 91 in the lever 61. In this instance, the member 60a enters the notch 65 in 6 the cam ring, and is swung outward on its pivot 62a, against the action of a spring 100, by the cam surface 69 of the cam ring, as heretofore described in connection with the member 60. However, the swinging of the member 60a, due 65 to the action of the cam surface 69, acts to bring a lever 92 carried by the member 60a into the path of the pin 70, which, consequent upon the revolution of the pattern roller 20, will engage the pawl, rocking it in a counter-clockwise position about its pivot 93, camming the latch 90 out of the recess 91, against the action of a spring 101 and raising both the pawl and the lever 61 out of engagement with the abutment 67. As 70 shown, an abutment 94 of the pawl 90 coacts with 75

the surface of the member 60a immediately after the pin 70 has rocked the compound lever 92 a distance sufficient to withdraw the nose 90 of the pawl out of engagement with the recess 91. Further rotation of the plate cylinder 20 thereupon positively rocks the lever 61 about its pivot 62.

From the foregoing description, it is apparent that I have provided a graining machine which will transfer a design in pigment from a suitable pattern roll to an offset printing roll, in which the period of contact between the two rolls is adjustably regulated, and which is so arranged as to permit the transfer of an entire pattern from a pattern roll to an offset roll of substantially the same diameter as the former and I accomplish this without danger of overlapping of the pattern and consequent blurring or distortion of the impression made by the offset roll on the material to be decorated.

20 I claim:

1. A surface decorating machine, comprising a frame, a pattern roll rotatably supported in said frame, means to apply pigment to said roll, a frame member movable toward and away from the pattern roll, means carried by said frame member to removably support an offset printing roll, and means interconnecting the movable frame member and the main frame member to lock them together with the two rolls contacting 30 with each other, and means to release said lock after the offset roll has made one complete revolution.

2. A surface decorating machine, comprising a frame, a pattern roll rotatably supported in said frame, power means to rotate said roll continuously, means to apply pigment to said roll, a second frame member pivotally carried by the first-named frame for movement toward and away from the pattern roll, means carried by the second named frame member to removably support an offset printing roll, means interconnecting the movable frame member and the main frame member to lock them together with the two rolls contacting with each other, means carried by such pattern roll to release said lock and means to positively limit the pressure between the two rolls.

3. A surface decorating machine, comprising a main frame, a pattern roll rotatably carried by said frame, means to rotate the pattern roll, a supplemental frame pivotally connected to the main frame, means carried by the supplemental frame to removably support a printing roll, means to prevent contact between the two rolls until a predetermined point in the revolution of the pattern roll is reached, means acting thereafter to lock the two rolls in engagement with each other.

4. A surface decorating machine, comprising a main frame, a pattern roll rotatably carried by said frame, a supplemental frame movably connected to the main frame, means carried by the supplemental frame to removably support a printing roll, means to prevent contact between the two rolls until a predetermined point in the revolution of the pattern roll is reached, means acting thereafter to lock the two rolls in engagement with each other, and means to release the lock when said predetermined point is again reached.

5. A surface decorating machine comprising a main frame, a supplemental frame movable toward and from the main frame, a pattern roll rotatably mounted in the main frame, means carried by the supplemental frame to removably sup-

port an offset printing roll, a latch to connect the two frames with the offset roll in contact with the pattern roll, means to prevent the operation of said latch and to maintain the two rolls separated until a predetermined point in the revolution of the pattern roll is reached, and means to release said latch and separate said rolls at a predetermined point in the revolution of the pattern roll.

6. A surface decorating machine comprising 10 a main frame, a supplemental frame pivotally connected to the main frame for movement toward and from the main frame, a pattern roll rotatably mounted in the main frame, means carried by the supplemental frame to removably support an offset printing roll, a latch to connect the two frames with the offset roll in contact with the pattern roll, means to supply pigment to the pattern roll, means to prevent the operation of said latch and to maintain the two 20 rolls separated until a predetermined point in the revolution of the pattern roll is reached, said means including a member pivotally carried by the latch and an annular member carried by the pattern roll, and means to thereafter release 25 the latch at a predetermined point in the revolution of the pattern roll.

7. A surface decorating machine comprising a main frame, a supplemental frame movable toward and from the main frame, a pattern roll 30 rotatably mounted in the main frame, power means to rotate the pattern roll, means carried by the supplemental frame to removably support an offset printing roll, a latch to connect the two frames with the offset roll in contact with the 35 pattern roll, means to prevent the operation of said latch to maintain the two rolls separated until a predetermined point in the revolution of the pattern roll is reached, said means including a member pivotally carried by the latch and an 40 annular cam member carried by the pattern roll, and means coacting with said pivoted member to thereafter release the latch at a predetermined point in the revolution of the pattern roll.

8. A graining machine comprising a main 45 frame, a supplemental frame pivotally connected to the main frame, a pattern roll rotatably supported in the main frame, adjustable means carried by the supplemental frame to rotatably support an offset printing roll, said supplemental 50 frame being movable to bring the offset roll into contact with the pattern roll or to separate it therefrom as desired, a latch to secure said frame members together, a pawl pivotally carried by the latch, an annular ring rotatable with the pattern 55 roll, said ring having a notch therein to permit the seating of the pawl at a predetermined time, a member rotatable with the pattern roll, said ring also being provided with a cam surface to rock the pawl about its pivot and cause a portion thereof to move into the path of said member, whereby contact between the member and the pawl will release said latch.

9. A graining machine comprising a main frame, a supplemental frame pivotally connected 65 to the main frame, a pattern roll rotatably supported in the main frame, an offset printing roll removably and rotatably carried by the supplemental frame, said supplemental frame being movable to bring the offset roll into contact with 70 the pattern roll or to separate it therefrom as desired, a latch to secure said frame members together, said latch comprising a latch member pivotally carried by one of said frames and an abutment carried by the other frame, a pawl 75

- pivotedly carried by the latch and an annular ring carried by one of said rolls and coating with the pawl to prevent contact between the offset and pattern rolls, said ring having a notch therein
- 5 to permit the seating of the pawl at a predetermined time, a cam rotatable with one of said rolls to rock the pawl about its pivot and cause a portion thereof to move out of its normal position, means rotatable with one of said rolls to coat 10 with said pawl when so moved to thereby release said latch and means to restore the pawl to its normal position.
10. A graining machine comprising a main frame, a supplemental frame pivotally connected to the main frame, a pattern roll rotatably supported in the main frame, a pigment applicator roll carried by the main frame and coating with the pattern roll, adjustable means carried by the supplemental frame to rotatably support an offset 15 printing roll whereby rolls of different diameters may be supported with their peripheries in contact with the peripheries of the pattern roll, said 20
- supplemental frame being movable to bring an offset roll into contact with the pattern roll or to separate it therefrom as desired, means to secure said frame members together, said means comprising a latch member pivotally carried by said supplemental frame and an abutment carried by the main frame, means to prevent engagement between the latch and the abutment until a predetermined point in the periphery of the pattern roll is in position to contact with the offset roll, 10 said last-named means comprising a pawl pivotally carried by the latch and an annular ring carried by the pattern roll and positioned to engage the pawl, said ring having a notch therein to permit the seating of the pawl at a predetermined time, a pin carried by the pattern roll, and said ring being provided with a cam surface to rock the pawl about its pivot and cause a portion thereof to move into the path of said pin, whereby contact between the pin and the pawl will release 20 said latch.

ROBERT H. McBEAN.
